DESIGN FOR A VELOCIPED

Giles E. Bullock, Rochester, N. Y., assignor to
E. C. Brown Co., Rochester, N. Y.

Application May 1, 1934, Serial No. 51,619

Term of patent 14 years

To all whom it may concern:

Be it known that I, Giles E. Bullock, a citizen of the United States, residing at Rochester, in the county of Monroe and State of New York, have invented a new, original, and ornamental Design for a Velocipede, of which the following is a specification, reference being had to the accompanying drawing, forming a part thereof.

Figure 1 is a view in side elevation of the velocipede, showing my new design.

Figure 2 is a detail view in front elevation of the fender.

Figure 3 is a horizontal sectional view of the fender taken on the line 3x—3x of Figure 2.

Figure 4 is a cross section of the fender of the

velocipede, the section being taken on the line 4x—4x of Figure 1.

The dominant feature of the invention resides in the front wheel fender shown in solid lines which has its outer edge concentric to the wheel, the sides of the forward portion of the fender wider than the sides of the rearward portion thereof and the wide sides of the forward portion overhanging and concealing a portion of the fork of the velocipede.

I claim:

The ornamental design for a velocipede, as shown and described.

GILES E. BULLOCK.
